(57) **CLAIM**

The ornamental design for a proprioceptive shaver as shown and described.

DESCRIPTION

FIG. 1 is a perspective view of a proprioceptive shaver of the present invention;

FIG. 2 is an alternative perspective view thereof;

FIG. 3 is a right view thereof;

FIG. 4 is a left view thereof;

FIG. 5 is a top view thereof;

FIG. 6 is a bottom view thereof;

FIG. 7 is a front view thereof;

FIG. 8 is a rear view thereof;

FIG. 9 is an alternative perspective view thereof; and,

FIG. 10 is a front perspective view of the proprioceptive shaver, shown in use, placed within a user's hand.

The broken lines depict portions of the proprioceptive shaver that form no part of the claimed design. In FIG. 10, the broken line depiction of the user's hand represents environmental subject matter that forms no part thereof.

1 Claim, 9 Drawing Sheets
